UNITED STATES PATENT OFFICE

ALFRED L. ROSENMUND, OF ROCKAWAY, NEW JERSEY, ASSIGNOR TO STAPLING MACHINES CO., A CORPORATION OF DELAWARE

BOX AND CRATE

Application filed June 1, 1929. Serial No. 367,763.

This invention relates to boxes and crates and particularly to sectional wirebound boxes and crates.

The invention is intended to provide an inexpensive reenforcement for a sectional box corner to stiffen and strengthen the box and to resist relative movement of adjacent sections of the box.

In the drawings:

10 Figure 1 is a perspective view of an open top box embodying the invention; certain parts being broken away for clearness of illustration.

15 Figure 2 is an enlarged perspective view of one of the illustrative devices for reenforcing a box corner.

Figure 3 is an enlarged top plan view of one corner of the box.

The illustrative box comprises four side 20 sections connected by encircling binders 1 secured to the several sections. Each side section comprises a sheet or sheets of side material 2, an interior cleat (not shown) and an exterior cleat 3. The interior cleat of 25 each section is secured to the side material adjacent the bottom edge, as shown in my co-pending application Serial No. 364,781, filed May 21, 1929, and the interior cleats of the several sections form an interior cleat 30 frame at the bottom of the box, which frame serves to resist inward displacement of the side sections at the bottom of the box and may serve to support a bottom section placed thereon or secured thereto. As shown in 35 Figure 1, the exterior cleat 3 of each section is secured to the side material adjacent the top edge, and serves to stiffen the side material against bulging at the top of the box. The exterior cleats 3 of the several sections may 40 serve as a support for a top section which may be nailed or otherwise secured to some or all of the exterior cleats. Exterior cleats 3 are preferably provided with a groove at either end to receive the encircling binder 1 which 45 overlies the exterior cleats.

In order to provide a box having a smooth inner surface free from projections, no interior cleats are provided at the top of the box. To prevent inward displacement of the 50 side sections at the top of the box and to

stiffen the box as a whole, reenforcing devices are applied at one or more of the top corners of the box, and preferably at all such corners.

As shown in the drawings, the illustrative 55 reenforcing device consists of a metal plate formed to have a body portion 4, an inner depending portion 5, an outer depending portion 6, and two laterally depending portions 7. The portions 5 and 6 depend downwardly from the portion 4 at substantially a right angle, and the portions 7 depend laterally from the portion 6 at substantially a 45 degree angle. Portions 7 are each preferably provided with an upwardly extending 60 spur 8 to prevent displacement of the device.

The reenforcing device is positioned and pressed over the box corner in the manner shown in Figures 1 and 3, with body portion 4 overlying the top of the side material 2, 70 inner depending portion 5 contacting with the inner surfaces of adjacent sections of side material, and portions 7 contacting respectively with adjacent exterior cleat ends.

The reenforcing device is preferably dimensioned to fit tightly in position with its depending portions pressed firmly against adjacent box parts to resist relative lateral shifting of adjacent sections of the box. Usually the firm contact between the depending 75 portions of the device and the box parts will prevent displacement of the device in the absence of the spurs 8, but, when spurs 8 are provided, they bite into the box parts and positively prevent displacement of the re- 80 enforcing device. In the illustrative box, the spurs 8 enter the grooves in the ends of the exterior cleats and cooperate with the other portions of the device to resist relative movement in any direction of adjacent sections of 85 the box.

A top or cover section (not shown) may be superimposed on the box and secured thereto in any suitable manner. Such a top or cover section and one method of securing it to the 90 box are shown in my co-pending application Serial No. 360,080, filed May 3, 1929.

The word "box" as used in the specification and claims is intended to include crates.

Among other advantages the invention pro- 100

vides a strong rigid sectional wirebound box having a smooth inner surface free from projections and which is adapted for use in the shipment of certain commodities not heretofore shipped in wirebound boxes.

I claim:

1. A sectional wirebound box comprising a plurality of separate side sections provided with exterior cleats and connected by binders secured thereto, and means to resist relative movement of adjacent sections; said means consisting of a substantially rigid device extending over the top of adjacent sections at each corner of the box and having an inner depending portion engaging the inner surfaces of adjacent sections and an outer depending portion having lateral extensions engaging adjacent ends of exterior cleats.
2. In a sectional wirebound box having exterior cleats, reenforcing means to resist relative movement of adjacent sections comprising a metal plate extending over the top of adjacent sections at a corner of the box and having outer and inner depending portions engaging respectively the outer and inner surfaces of adjacent sections, the outer depending portion being located between adjacent cleat ends.
3. In a sectional wirebound box having exterior cleats, reenforcing means to resist relative movement of adjacent sections comprising a metal plate extending over the top of adjacent sections at a corner of the box and having an inner depending portion engaging the inner surfaces of adjacent sections and an outer depending portion engaging the ends of adjacent exterior cleats.
4. In a sectional wirebound box having exterior cleats, reenforcing means to resist relative movement of adjacent sections comprising a metal plate extending over the top of adjacent sections at a corner of the box and having an inner depending portion engaging the inner surfaces of adjacent sections and an outer depending portion having lateral extensions engaging adjacent ends of exterior cleats.
5. In a sectional wirebound box having exterior cleats, reenforcing means to resist relative movement of adjacent sections comprising a metal plate extending over the top of adjacent sections at a corner of the box and having an inner depending portion engaging the inner surfaces of adjacent sections and an outer depending portion having lateral extensions provided with spurs engaging adjacent ends of exterior cleats.

In testimony whereof, I have signed my name to this specification this 29th day of May, 1929.

ALFRED L. ROSEN MUND.
